US0D1091765S

(12) United States Design Patent (10) Patent No.: US D1,091,765 S
(45) Date of Patent: * Sep. 2, 2025

(54) FLUSHING APPARATUS

(71) Applicant: Xiamen Onefami Technology Co., Ltd., Xiamen (CN)

(72) Inventors: Jianfang Liu, Xiamen (CN); Bin Chen, Xiamen (CN)

(73) Assignee: Xiamen Onefami Technology Co., Ltd., Xiamen (CN)

() Term: 15 Years

(21) Appl. No.: 29/899,568

(22) Filed: Aug. 10, 2023

(51) LOC (15) Cl. 23-06

(52) U.S. Cl.

USPC D23/226

CLAIM

The ornamental design for a flushing apparatus as shown and described.

DESCRIPTION

FIG. 1 is a perspective view of a flushing apparatus showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a perspective view in an expanded state.

Broken lines in the drawings depict portions of the flushing apparatus that form no part of the claimed design.

1 Claim, 7 Drawing Sheets
